UNITED STATES PATENT OFFICE.

GEORG STEIDINGER, OF PHILADELPHIA, PENNSYLVANIA.

HAND PLANE.

Application filed April 16, 1924. Serial No. 706,906.

To all whom it may concern:

Be it known that I, GEORG STEIDINGER, a citizen of the Republic of Germany, having declared my intentions of becoming a 5 citizen of the United States, residing at Philadelphia, in the county of Philadelphia and State of Pennsylvania, have invented certain new and useful Improvements in Hand Planes, of which the following is a 10 specification.

One object of my invention is to provide an improved hand plane of such construction that it will be of particular value for planing work which is ordinarily difficult 15 and tedious; my improved plane being so shaped and constructed that it can be readily and conveniently operated by either hand or at various angles to accurately plane such fine work as grooved, corrugated, 20 fluted or irregularly shaped rails, banisters, mouldings, and cabinet work. Furthermore, my improved plane is of such formation that it can be used to easily approach and plane such rails, etc., on either side and to plane 25 work which is located in positions ordinarily difficult or impossible to plane owing to insufficient working room.

Another object is to make my improved plane of a durable and light weight construction and to provide improved means for 30 adjusting the cutting blades or bits.

A further object is to make my improved plane of such construction that certain of the parts can be readily adjusted relatively 35 to the bits or replaced by other parts so as to allow various uses to suit different requirements.

Another object is to provide a structure 40 by which the bits can be finely and accurately adjusted and maintained in position by a simple and easy movement on the part of the operator and so that the work done will be of such character as to require little, if any, refinishing after the planing operation.

These objects and other advantageous 45 ends which will be set forth hereinafter, I attain in the following manner, reference being had to the accompanying drawing, 50 in which—

Figure 1 is a side elevation of a hand plane made in accordance with my present invention,

Figure 2 is an end view of the plane shown in Figure 1,

55

Figure 3 is a top plan view of Figure 1.

Figure 4 is a top plan view of one of the bit-retaining members constituting a part of my invention,

Figure 5 is a sectional view taken on the 60 line 5—5 of Figure 4 with a retaining or suspension pivot bolt which I preferably employ,

Figure 6 is a sectional view taken on the 65 line 6—6 of Figure 5,

Figure 7 is an end view of the member shown in Figure 4, and

Figure 8 is an elevational view showing a modified form of my invention.

Referring to the drawing and particularly to Figures 1 to 7 inclusive, 10 represents the main body portion of my improved plane which is preferably made of aluminum. This body portion includes a neck 11 which joins two planing stocks 12 and 13, said stocks being arranged in stepped formation as clearly shown in Figure 1. The stock 12 includes an adjustable section 14, and the stock 13 includes an adjustable section 15. Viewed from Figure 1 these 15 sections 14 and 15 are adjustable vertically, and are secured in said adjustable manner to extensions or arms 16 and 17 by screws 18, the sections slidably interlocking with the arms with a tongue and groove construction 19 as clearly shown in Figures 2 and 3. It will be noted that by loosening the screws 18, the sections 14 and 15 can be adjusted or if desired, said sections can be removed, by removing the screws 18, and 20 other sections of different shapes (not illustrated) can be substituted therefor.

The stock 12 has a recess 20 which extends therethrough from side to side and at its bottom forms an interruption 21 of the 25 planing surface 22 of the stock 12, the forward portion of said planing surface being formed by the section 14. In like manner the stock 13 has a recess 23 which extends from side to side and at its top, viewed from 30 Figure 1, forms an interruption 24 in the planing surface 25, said planing surface at its front being formed by the section 15.

The wall 26 of the recess 20 is preferably concave in the direction of its height as 35 shown in Figure 1 and forms a support or

backing for the bit 27, said bit being normally straight in the direction of its length so that when pressed against the wall 26 it will bow or slightly flex so as to be kept under tension.

A bit-retaining member 28 is located within the recess 20 and serves jointly as a retaining and adjusting member for the bit 27. This member 28 as shown in detail in Figures 4 to 7 inclusive, has a cavity 29 which communicates with a slot 30 in the top of said member. The top surface 31 is preferably made convex to a slight degree and includes a notch 32. A bolt 33 has flat opposite side portions 34 adapted to fit within the slot 30, and a round head 35 adapted to fit within the cavity 29. The bolt 33 extends upwardly through a hole 36 in the arm 16 and at its top is screw threaded to receive a nut 37, said nut 37 is adapted to bear upon the top surface 38 of said arm 16. The hole 36 is preferably made slightly larger in diameter than is the bolt 33 to allow a slight lateral movement of the bolt for a purpose hereinafter rendered obvious. An adjusting screw 39 fits within a tapped hole in the arm 16, said hole leading entirely through said arm 16 from the top surface 38 to the recess 20. The lower end of said screw 39 is adapted to freely fit in the notch 32. The surface 40 of the member 28 is adapted to engage the bit within its length and press it against the surface 26, and in this manner the bit is securely held and a slight adjustment of the cutting edge 41^a can be had by turning the adjusting screw 39 so as to cause the member 28 to slightly rock and vary the amount of flex of the bit 27. In like manner the wall 26^a of the recess 23 is concave within its height and forms a support or backing for the bit 27^a, said bit being normally straight in the direction of its length so that when pressed against the wall 26^a it will bow or slightly flex and be kept under tension. A bit-retaining member 28^a is located within the recess 23 and serves jointly as a retaining and adjusting member for the bit 27^a. The member 28^a is similar in construction to the member 28 above described and includes a cavity 29^a in which is positioned the round head 35^a of a bolt 33^a which extends through a hole 36^a in the arm 17 of the stock 13 and is provided with a nut 37^a. An adjusting screw 39^a fits within a tapped hole in the arm 17 and bears upon the member 28^a in a manner similar to that described in connection with the screw 39 and member 28. In other words the bolt 33^a has a flat portion which engages within a slot similar to the slot 30, and the bit 27^a is therefore retained and adjustable in the same manner as is the bit 27.

Considering that the stock 12 is to be used for planing purposes, the workman grasps the stock 13 in his hand with the

surface 25 engaging the palm of the hand and in this position the bit 27 is forward of the bit 27^a, and the thumb and first finger of the workman can embrace the opposite sides of the stock 12 adjacent the member 28; the space 41 above the surface 38 and below the plane of the surface 25 allowing the first finger of the hand to rest against and in front of the portion 42 of the stock 13, a part of the palm of the hand engaging the surface 43. Thus the construction allows a secure and comfortable hand hold which allows sufficient pressure of the hand to move the plane for planing purposes. Further than this the space 41 provides clearance to allow the plane to be moved in various paths without interference or striking against adjacent parts of the work.

In like manner, when the stock 13 is being used for planing purposes, the stock 12 can be grasped in the hand with the surface 22 against the palm of the hand, the space 41^a serving in a capacity similar to that described in connection with the space 41, and the thumb and the first finger of the hand can embrace the stock 13 adjacent opposite sides of the member 28^a. It will thus be noted that when either one of the stocks is being used for planing purposes, the bit of the planing stock will be positioned to the rear of the bit which is not doing the planing, thus allowing the workman to centralize his attention solely on the stock which is doing the work, the other stock being concealed by the workman's hand. Furthermore, in the construction illustrated, when either one of the stocks is being used for planing purposes, the other stock and bit will be to the rear of the cutting edge of the bit which is doing the planing.

It has been found in actual use of the plane that the arrangement and construction above set forth enables parts of work to be planed which previously could not be practically planed owing to interference of the workman's hand and parts of the plane stock.

The planing surfaces 22 and 25 can be made any suitable shape to suit special work as can also be the cutting edges of the bits 27 and 27^a.

The neck 11 centrally connects the stocks 12 and 13 and thus it is possible to provide the unobstructed spaces 41 and 41^a.

Furthermore, the provision of the longitudinally extending arms 16 and 17 provide a convenient mounting for the adjusting and securing means for the respective bits.

In Figure 8, I have shown a single-stock plane embracing certain of the advantageous features of my invention as above described such for example as the means for retaining and adjusting the bit and forward section of the stock, and I have therefore given corresponding parts similar reference characters

to those described in connection with the plane previously set forth. In said Figure 8, however, I have illustrated a rearwardly extending downwardly curved portion 44 serving as a rest for the rear portion of the palm of the hand when the plane is grasped in the hand.

Having thus described my invention what I claim as new and desire to secure by Letters Patent is:

1. A hand plane including a body portion with two planing stocks arranged in stepped formation and a portion connecting said stocks; and bits secured to said stocks, said connecting portion being located between the cutting edges of said bits whereby as one stock is being used for planing purposes the other stock forms a handle for the manipulation of the plane.
2. A hand plane including a body portion with a centrally positioned neck connecting two planing stocks, said planing stocks being arranged in stepped formation whereby as one stock is being used for planing purposes the other stock forms a handle for the manipulation of the plane.
3. A hand plane including a body portion with a centrally positioned neck connecting two planing stocks, said planing stocks being in stepped formation with oppositely disposed planing surfaces whereby as one stock is being used for planing purposes the other stock forms a handle for the manipulation of the plane.
4. A hand plane including a body portion with two planing stocks arranged in stepped formation with oppositely disposed planing surfaces whereby as one stock is being used for planing purposes the other stock forms a handle for the manipulation of the plane, said body portion including arms extending longitudinally in opposite directions; and bit-retaining means carried by said arms.
5. A hand plane including a body portion with two planing stocks arranged in stepped formation with oppositely disposed planing surfaces whereby as one stock is being used for planing purposes the other stock forms a handle for the manipulation of the plane, said body portion including arms extending longitudinally in opposite directions; and bit-retaining means carried by said arms, said stocks including sections adjustably se-

cured to said arms and providing portions of said planing surfaces.

6. A plane having a portion including a recess providing a wall; a bit for engagement with said wall; a member having a cavity; a bolt supported by said portion and having an enlarged portion within said cavity whereby said member is suspended; and adjustable means for moving said suspended member to cause it to press against said wall.

7. A plane having a portion including a recess providing a wall; a bit for engagement with said wall; a bit retaining and pressing member movably suspended within the recess, the connection for said member including an enlarged cavity in the body of said member and a part comprising a head positioned within said cavity with a supporting stem passing loosely through the member; and adjustable means for moving said member to cause it to bear upon said bit.

8. A plane including a portion providing a recess; a bit for engagement with a wall of the recess; a member having a slot and an enlarged cavity communicating with the slot; a bolt carried by said portion and having a part extending through said slot and an enlarged portion positioned within said cavity whereby said member is movably suspended; and means for moving said member to press said bit and hold it against said wall.

9. A plane including a portion providing a recess; a bit for engagement with a wall of the recess; a member having a slot and an enlarged cavity communicating with the slot; a bolt carried by said portion and having a part extending through said slot and an enlarged portion positioned within said cavity whereby said member is movably suspended; and means for moving said member to press said bit and hold it against said wall, said latter means comprising a screw, said member having a notch for engagement with a part of the screw.

In testimony whereof I have signed my name to this specification in the presence of two subscribing witnesses.

GEORG STEIDINGER.
